UNITED STATES PATENT OFFICE

167,185

PLAY BURRO

Robert H. Wendt, Evanston, Ill.

Application June 11, 1951, Serial No. 15,488

Term of patent 14 years

(Cl. D34—15)

To all whom it may concern:

Be it known that I, Robert H. Wendt, a citizen of the United States, residing at Evanston, in the county of Cook and State of Illinois, have invented a new, original, and ornamental Design for Play Burro, of which the following is a specification, reference being had to the accompanying drawing, forming a part hereof.

Fig 1 is a side elevational view of a play burro showing my new design;

Fig. 2 is a top plan view; and

Fig. 3 is a front elevational view.

I claim:

The ornamental design for a play burro, as shown.

ROBERT H. WENDT.
